UNITED STATES PATENT OFFICE.

CAROLINE FOOTE MARSH, OF NEW YORK, N. Y.

VITREOUS ARTICLE AND PROCESS OF TREATING SAME.

No. 842,218.

Specification of Letters Patent.

Patented Jan. 29, 1907.

Application filed February 2, 1906. Serial No. 299,103.

To all whom it may concern:

Be it known that I, CAROLINE FOOTE MARSH, a citizen of the United States, and a resident of the borough of Manhattan, city, county, and State of New York, have invented certain new and useful Improvements in Vitreous Articles and Processes of Treating Same, of which the following is a specification.

My invention relates to vitreous articles and process of treating same, and particularly to the protection and ornamentation of glass articles, including bottles and the like, by means of metal bands, insertions, or other ornamental or protecting parts securely affixed thereto and forming a part thereof.

It refers to the glass article itself provided with such a metallic ornamentation and protection and to the process of making such article.

The invention further consists of various combinations and details which will be described in the specification and pointed out in the claims.

The essence of the invention resides in forming the glass article either during the process of manufacture or afterward with depressed portions which are afterward filled with an electrically-deposited metallic ornamentation or band, whereby the metal is firmly secured to the glass article, preferably with the meeting edges of the glass and the metal flush with each other, and in any case so that the metal parts are intimately united with the glass and cannot be dislodged therefrom without breakage.

In the drawings, Figure 1 is an elevation of a bottle embodying my invention. Fig. 2 is a vertical section of the same, and Fig. 3 a fragmentary section showing a modification.

1 designates the body of a bottle, of which 2 is the neck. The bottle 1 is either formed in the process of manufacture with the depressed portions 3 or such depressions are produced in the surface of the bottle after its manufacture. The depressions 3 are then filled with a metallic ornamentation 4, shown in the present case as a series of concentric bands surrounded by a sunburst or plurality of waved radial lines.

As already stated, the depressed portions 3 may be formed in the bottle when it is blown or molded; but I ordinarily prefer to form the bottle in the usual manner and afterward to cut out these depressions by means of a sand-blast or by chemical means. Where

the depressions are made by a sand-blast, their edges 11 will be substantially at right angles with the adjacent surface and with the bottom of the depression. Where, however, as shown in Fig. 3, I form a depression 12 by etching away the surface of the glass by means of hydrofluoric acid or the like, the edges 13 of the depression will be undercut, as shown, thereby forming a more secure anchorage for the metal portion 4.

Whether the depressed portions are cut away by mechanical or chemical means, in any case their surfaces will be roughened, which will afford a more secure adhesion of the metallic portions thereto. These depressed portions, whether formed in the course of manufacture or afterward, as described, are ordinarily covered with metal by first coating them with a composition composed of a metal having a good electric conductivity, together with a suitable flux and ordinarily a powdered vitreous material. The bottle or other article is then fired in a kiln in the usual manner to fuse this composition, and the article is then placed in an electrolytic bath and the metal parts deposited thereon. This process is preferably continued until the edges of the metal parts are flush with the adjacent glazed surface, so that the meeting edges of the glass and of the metal are intimately united and in the same plane. It will be seen that the metal which fills the depression is a solid mass, the contacting—*i. e.*, the lower and lateral—surfaces of which are united by the firing operation to the vitreous article.

It is evident that my invention may be applied to other articles beside bottles and that it is capable of being varied within considerable limits without departing from its spirit.

On December 28, 1905, I filed an application for an article of pottery and process of treating same, which application has received Serial No. 293,567. I do not intend to claim in this application anything shown or described therein.

What I claim is—

1. A vitreous article having a portion of its surface depressed and roughened, such depressed portion being filled with a metal, the contacting surface of which is fired onto the vitreous article.

2. A vitreous article having a portion of its surface depressed and roughened, said depressed portion being formed with undercut

edges and being filled with a metal, the contacting surface of which is fired onto the vitreous article.

3. A vitreous article having a portion of its surface depressed and artificially roughened, said depressed portion being covered with a composition fired thereon, and a filling of metal intimately united with said covering.

4. A vitreous article having a portion of its surface depressed and artificially roughened, said depressed portion being covered with a composition fired thereon, and a filling of metal intimately united with said covering, the meeting edges of said depressed portions and of said metal filling being flush with each other.

5. A process of treating vitreous articles having portions of their surfaces depressed and roughened, comprising the filling of such depressed portion by a mass of metal, the contacting surface of which is fired onto the vitreous article.

6. A process of treating vitreous articles having portions of their surfaces depressed and roughened, comprising the filling of such depressed portions by a mass of metal, the contacting surface of which is fired onto the vitreous surface, the meeting edges of the depressed portion and of the metal being flush with each other.

7. A process of treating vitreous articles having portions of their surfaces depressed,

comprising the roughening of the surfaces of said depressed portion, the application to such depressed portions of a composition containing a metal and a flux, the firing of the article to fuse such composition, and the deposition upon the fused composition of a metal.

8. A process of treating vitreous articles comprising the removal of portions of the surfaces of such articles to form depressions, the application to such depressed portions of a composition containing a metal and a flux, the firing of the article to fuse such composition, and the deposition upon the fused composition of a metal of sufficient thickness to fill said depressed portions.

9. A process of treating vitreous articles comprising the removal of portions of the surfaces of such articles, the undercutting of the article at the edges of such depressed portion, the application to the depressed portion of a composition containing a metal and a flux, the firing of the article to fuse such composition, and the deposition upon the fused composition of a metal.

In testimony whereof I have signed this specification in the presence of two subscribing witnesses.

CAROLINE FOOTE MARSH.
